UNITED STATES PATENT OFFICE.

DONALD A. CUMFER, OF CHICAGO, ILLINOIS.

ROOFING.

Application filed February 7, 1921. Serial No. 443,016.

To all whom it may concern:

Be it known that I, DONALD A. CUMFER, a citizen of the United States, residing at Chicago, in the county of Cook and State of Illinois, have invented certain new and useful Improvements in Roofing, of which the following is a specification.

The invention relates to improvements in roofing.

10 One of the objects of the invention is to improve shingle-simulating strips in which a plurality of shingle-like sections are joined together in a single strip.

15 A particular object of the invention is to divide the shingle-like sections by kerfs, indentations, depressions or other visible token of division giving the appearance of actual separation, or slots, between the shingles.

20 Another object is to provide a shingle strip in which both of its sides are covered with crushed or flaked slate, or the like. The slate of the respective sides is, preferably, of different colors, so that either side may be 25 exposed to observation on the roof and variations in decorative effect may be thus inexpensively produced.

Another object is to produce a strip in which the transversely extending depressions or kerfs extend from the longitudinal edges towards the center of the strip on opposite sides thereof, so that the kerfs on the underside of the strip, whichever side is exposed to the weather, are not located immediately below the exposed surface.

30 Another object is to coat both sides of the strip, or roofing sheet, with slate receiving plastic and with slate, thereby preventing "buckling" on the roof, due to the unequal 35 expansion and contraction of the product.

Another object is to improve the quality of the shingle strip by entirely covering both sides thereof with a material that is not sticky or viscid.

40 Another object is to stiffen the sheet by application of the flaky material on both sides, so that it will be substantially unaffected, when on the roof, by wind pressure.

45 Other, further and more specific objects of the invention will become readily apparent, to persons skilled in the art, from a consideration of the following description, when taken in conjunction with the 50 drawings, wherein:—

Fig. 1 shows the sheet of roofing mate-

rial coated on both sides with slate, or the like, and the lines at which the sheet is to be divided to make the shingle-simulating strips.

55 Fig. 2 shows a section taken on line 2—2 of Fig. 1.

Fig. 3 shows the sheet of roofing material covered on both sides with slate and having the spaced kerfs in such way that the sheet 65 is to be divided longitudinally and transversely into the shingle simulating strips.

60 Fig. 4 is a perspective view of a fragment of a finished strip.

70 In all the views the same reference characters represent corresponding parts.

75 10 represents a sheet of roofing material comprising a fibrous base 11 upon which has been applied a relatively hard plastic material 12 of asphaltic nature usually employed in making roofing material of the type disclosed herein. 13 is a covering of colored granular or flake slate, or the like, partially embedded in the asphalt. 13' is a similar covering of slate of preferably different color so that either side may be exposed on a roof to produce variegated color effect.

80 85 Shingle-like tabs or butts 14 may be produced on each side of the strip 15 by depressing the slate into the black asphalt, thus making stripes or kerfs and the visual effect of separation between adjacent butts. Shingle-like representations are thus presented to view on a roof. Similar kerfs or 90 stripes of demarcation are made on the opposite side of the strip extending from the longitudinal edge toward the center of the strip and preferably in the same transverse plane with similar kerfs on the opposite side 95 of the strip. This renders the strip as a whole more flexible longitudinally, so that the shingles will lay closer to the deck without reducing their rigidity in transverse planes.

100 100 Figs. 1 and 3 show how the shingle strips may be cut from a sheet of roofing material without waste of material. By making kerfs or depressions 16 instead of actual separations between the shingle butts the strip is more durable and the roof made thereby is more weather resistant.

110 Having described my invention what I claim as new and desire to secure by Letters Patent, is:—

1. A shingle strip having a plurality of shingle-like sections covered on both sides

with a divided mineral, and having visible indications on both sides in the same respective transverse planes dividing the strip into sections, said indications extending from each longitudinal edge toward the transverse center of the strip.

2. A shingle strip provided with a suitable base having a plastic coating of asphalt on each side; a covering of divided mineral 10 of contrasting color partly embedded in said coating and transversely extending indicating kerfs at intervals in which the covering is entirely embedded in said asphalt, said kerfs extending from opposite edges on opposite sides of the strip, towards the other edge.

3. A shingle simulating roofing unit comprising a fibrous asphalt-bearing sheet having its opposite sides coated with plastic asphalt and said asphalt coatings each bearing a coating of fire-resistant material and relatively narrow depressions at spaced intervals, the stripes made thereby extending from the respective edges toward the transverse center of the unit, said stripes provided by submerging the fire resistant material into the asphalt to produce short black stripes, whereby either side of the unit may be exposed upon a roof.

In testimony whereof I hereunto subscribed my name.

DONALD A. CUMFER.
